UNITED STATES PATENT OFFICE.

ANDREW KERESZTURY, OF CHICAGO, ILLINOIS.

AEROPLANE-RADIATOR.

1,164,820.

Specification of Letters Patent. Patented Dec. 21, 1915.

Application filed November 9, 1914. Serial No. 871,196.

To all whom it may concern:

Be it known that I, ANDREW KERESZTURY, a citizen of the United States, residing at Chicago, in the county of Cook and State 5 of Illinois, have invented certain new and useful Improvements in Aeroplane-Radiators, of which the following is a specification.

The radiator which is the subject matter 10 of the present application for patent is designed more particularly for use in connection with flying machines, the construction of the radiator and the arrangement of the component parts thereof being such that the 15 same may be mounted on the supporting plane of the machine without presenting any appreciable resistance to the travel of the machine, and its position being such that no useful space is sacrificed.

20 In order that the invention may be better understood, reference is had to the accompanying drawing in which—

Figure 1 is a plan view of the invention, partly broken away, and Figs. 2 and 3 are 25 enlarged sections on the lines 2—2 and 3—3, respectively, of Fig. 1.

Referring specifically to the drawing 5 denotes the supporting plane of a flying machine. If the machine is of the biplane or 30 monoplane type, the plane 5 will be the top plane of the machine. The radiator which is the subject matter of the present application for patent is mounted on this plane, and it is constructed and arranged as follows:

35 The radiator comprises front and rear tanks 6 and 7, respectively, and a shallow, flat conduit 8 extending therebetween and in communication therewith. The water enters the tank 6 and passes through the conduit 8 to 40 the tank 7. The conduit is very shallow, and the water therefrom flows in a thin film between the tanks, and as the walls of the conduit are exposed to the air the water is quickly cooled by radiation. In order to 45 prevent the wall of the conduit from meeting or becoming dented and thus obstructing the circulation of the water, a series of spacing members 9 is mounted in the conduit between the top and bottom walls thereof.

50 These spacing members extend in the direction of the length of the conduit, and they are channel-shaped in cross-section. The water therefore not only flows in the spaces between the members but it also flows along 55 the channels thereof. The water is thus divided into thin streams, and the members

present an additional heat-radiating surface. The water is carried by the tank 6 from the water jacket of the engine by a conduit 10, and a conduit 11 carries the 60 water back to the water jacket. A pump will be employed as usual to maintain the circulation of the water, but as this pump forms no part of the present invention, it has not been illustrated.

65 The plane 5 is reinforced at its front and rear edges by ribs 12 and 13, respectively. Midway between the ends of the plane, these ribs are cut away and in the spaces thus had the tanks 6 and 7 are mounted. The tanks 70 are dimensioned and shaped in cross section to conform to the dimensions and shape of the ribs, in view of which the surface of the plane is left smooth and devoid of projecting parts, and the tanks therefore offer 75 no resistance to the travel of the machine.

A longitudinal reinforcing rail 14 is mounted against the back of the tank 6, and a similar rail 15 is mounted in front of the tank 7.

80 The plane 5 is composed of a light frame work comprising the ribs 12 and 13 and vertically spaced ribs 16 extending from the front to the rear of the plane, with a top and bottom canvas or other fabric cover 17. 85 For a distance corresponding to the width of the radiator, the ribs 16 stop at the rails 14 and 15 to leave the open spaces for the tanks 6 and 7. The radiator is inserted into these spaces from below so that the conduit 90 8 lies beneath the plane. Above the radiator, the cover of the plane is left off and the conduit 8 is fastened to the ribs 16 by pins 18 passing therethrough and through the walls of the conduit, as well as through the spacing members 9. Thus the bottom, as well as the top, of the conduit is left exposed to the air. The rails 14 and 15 are located between the top and the bottom ones of the ribs 16 95 and serve to space the same. Additional 100 spacing blocks 19 may also be employed, through which the pins 18 pass. Between the heads of the pins and the bottom wall of the conduit are interposed washer strips 20.

105 The tank 6 is provided with a filling aperture provided with a suitable closure 21.

I claim:

1. The combination with the supporting plane of a flying machine, said plane having 110 an opening intermediate its ends, of a radiator carried by the plane and having its sur-

face exposed to the air, said radiator comprising tanks mounted at the front and rear of the opening in the plane and having a shallow connecting conduit extending 5 across the opening.

2. The combination with the supporting plane of a flying machine, of a radiator carried by said plane and having its surface exposed to the air, said radiator comprising 10 tanks mounted at the front and rear edges of the plane and having a shallow connecting conduit, and reinforcing members mounted in the conduit between opposite walls thereof, said members being spaced apart and 15 channeled in cross section.

3. The combination with the supporting plane of a flying machine, of a radiator car-

ried by said plane and having its surface exposed to the air, said radiator comprising tanks mounted at the front and rear edges 20 of the plane and having a shallow connecting conduit, reinforcing members mounted in the conduit between opposite walls thereof, said members being spaced apart and channeled in cross section, and fastening 25 means passing through the walls of the conduit and the reinforcing members.

In testimony whereof I affix my signature in presence of two witnesses.

ANDREW KERESZTURY.
